(57) **CLAIM**

We claim the ornamental design for a display screen with a graphical user interface for an ultrasound system, as shown and described.

DESCRIPTION

FIG. 1 is a first image in a sequence of a graphical user interface, shown as a front elevation view of a display screen, showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof;

FIG. 15 is a fifteenth image thereof;

FIG. 16 is a sixteenth image thereof;

FIG. 17 is a seventeenth image thereof;

FIG. 18 is an eighteenth image thereof;

FIG. 19 is a nineteenth image thereof;

FIG. 20 is a twentieth image thereof; and,

FIG. 21 is a twenty first image thereof.

The appearance of the graphical user interface transitions between the images is shown in FIGS. 1-21. The process or period in which one image transitions to another forms no part of the claimed design. The outermost rectangular broken lines illustrate the display screen. The remaining broken lines illustrate portions of the graphical user interface. None of the broken lines form part of the claimed design.
